UNITED STATES PATENT OFFICE.

GEORGE B. DUSINBERRE, OF ELMIRA, NEW YORK, ASSIGNOR TO GLENORA HARMONICA COMPANY, INC., OF ELMIRA, NEW YORK, A CORPORATION OF NEW YORK.

HARMONICA.

Application filed May 19, 1921. Serial No. 470,870.

To all whom it may concern:

Be it known that I, GEORGE B. DUSINBERRE, a citizen of the United States, residing at Elmira, in the county of Chemung 5 and State of New York, have invented a certain new and useful Improvement in Harmonicas, of which the following is a full, clear, and exact description.

This invention relates to musical instruments of the harmonica type, and has for its chief object to improve the musical possibilities of instruments of this type by increasing the number of available reed plates so as to make possible a greater combination of chords than is obtainable with a harmonica as usually constructed with two reed plates.

In my improved instrument three or more reed plates are provided, carried by a plate holder which can be shifted by the operator relative to the mouth piece so as to render effective various combinations of plates.

In the accompanying sheet of drawings 25 showing both a three and five plate harmonica embodying my invention, Fig. 1 is a side view of a three plate harmonica embodied in a form which is very satisfactory, parts being broken away; Fig. 2 is a top 30 plan view of the same; Fig. 3 is a side view of the plate holder with the casing and mouth piece removed; Fig. 4 is a longitudinal sectional view substantially along the line 4—4 of Fig. 1; Fig. 5 is an end 35 view looking toward the right of Fig. 1 with one end of the casing removed; Fig. 6 is an enlarged transverse sectional view; Fig. 7 is a view similar to Fig. 4, showing a five plate instrument; Fig. 8 is a trans- 40 verse sectional view of the same; Fig. 9 is a transverse sectional view of a three plate instrument showing a different way 45 of forming the casing and mouth piece; and Fig. 10 is an end view of the same.

Referring first to Figs. 1 to 5, it will be observed that the instrument here shown, includes a cylindrical casing 10, with a mouth piece 11 having spaced air passageways 12. In this instance the mouth piece is 50 formed by a separate member secured to the casing by screws 13, the casing having openings 12^a which register with the passageways 12 of the mouth piece.

Inside the casing, and in this case coaxial 55 therewith, is a plate holder provided in this

instance with three reed plates 14, 15 and 16, separated by two chambered spacers 17 and 18, having passageways, chambers or cells 19 extending therethrough. The reeds of the reed plates communicate with these 60 passageways so that they may be affected in the usual manner by air drawn or forced through the passageways.

The plate holder may be formed in different ways, but in the embodiment shown 65 the chambered spacers 17 and 18 consist of two separate members with the middle reed plate clamped between them, and with their outer sides covered by the two outer reed plates, the chambered spacers and the reed 70 plates being solidly clamped together by transverse screws 20 passing through the ends of the chambered spacers and through the ends of the reed plates beyond the end- 75 most reeds. In this instance also, the screws 20 hold against the two outermost reed plates two metal pieces 21 which extend lengthwise of the reed plates, and have inner portions bearing against the plates be- 80 tween the reeds. Likewise these pieces project laterally outward into contact with the inner wall of the cylindrical casing 10.

The oppositely disposed edges of the spacers 17 and 18 are rounded, the curvature conforming accurately to the curvature of the casing, the inside wall of which closely engages with a spring action the curved top and bottom edges of the spacers with sufficient tightness to form a practi- 85 cally air-tight joint, but at the same time 90 to permit the plate holder to be turned inside the casing. Of course, the contact be- 95 tween the rounded edges of the spacers and the inner wall of the casing does not form an air-tight joint in the strictest sense of the term, but nevertheless the fit of the holder inside the casing is such as to prevent any material amount of leakage.

The casing is completed by the addition 100 to the cylindrical body 10 of two end caps 22, with inturned flanges fitting over the cylindrical body portion of the casing. These end caps are in this instance secured by screws 23, to the ends of the plate holder. Though I do not wish to be confined to 105 this particular construction or method of shifting the plate holder inside the cylindrical part of the casing, nevertheless the attachment of the caps to the plate holder with the caps capable of turning on the body por- 110

- tion of the casing does provide a very effective way of turning the plate holder inside the body portion of the casing. In this instance, as will be observed in Fig. 2, the in-turned flanges of the caps have notches 22, which permit them and the plate holder to be turned a predetermined amount with reference to the mouth piece and the body portion of the casing.
- 10 One important characteristic of the instrument is the provision of sets of openings in the casing for the inflow or outflow of air. For a three plate instrument as preferably constructed this requires three sets of openings properly spaced circumferentially of the casing. These are indicated in the drawings at 24, 25 and 26. The opening 24 consists in this instance of a slot extending lengthwise of the body portion 15 of the casing, diametrically opposite from the mouth piece. This slot in addition to forming a passageway for air, also makes provision for the necessary spring in the casing to cause it to properly frictionally engage the rounded edge portions of the plate holder, since the slot forms in effect two more or less independent portions clamping or embracing the plate holder with a yieldable action. The other two sets 20 of openings 25 and 26 are located on both sides of the middle slot 24 and may consist of round openings whose number and spacing correspond to the number and spacing of the reeds of the reed plates.
- 25 This instrument is used in the following manner: If the plate holder is turned as shown in Figs. 5 and 6 so that the chambers or cells 19 of the right hand spacer 18 are in line with the openings of the mouth piece, then the upper ends of the cells of the left hand spacer 17 are closed by the casing, as clearly shown in Fig. 6. However, the lower ends of the cells of the left hand spacer 17 now register with slot 24. With this arrangement the two reed plates 15 and 16 become effective, one as a "draw" plate and the other as a "blow" plate, and the slot 24 and openings 26 become effective one for the admission of air drawn through one reed 30 plate and through the mouth piece, and the other for air blown through the mouth piece and through the other reed plate. Similarly, when the plate holder is turned so that the chambers or cells of the left hand spacer 17 register with the openings of the mouth piece, then the reed plates 14 and 15 become available, and the reed plate 16 becomes ineffective, the slot 24 and openings 25 then being used, one to admit air which 35 is drawn through one reed plate, and the other for the exhaust of air blown through the other reed plate. It will be understood that the operator by taking hold of one end cap can turn the reed plate as desired, from 40 one position to the other, thus changing the

combination of plates that are effective for playing.

While plates of different keys may be utilized, I might say by way of example, that I have made a very effective instrument utilizing two standard "C" plates, together with a "G" blow plate.

It is not at all essential that the casing and mouth piece be formed as in Figs. 1 to 5, as will be evident by comparison of these figures with Figs. 9 and 10. As already explained in Figs. 1 to 5, the casing is formed from one cylindrical piece to which the mouth piece is attached, the casing having a longitudinally extending slot diametrically opposite from the mouth piece. In Figs. 9 and 10 the body portion of the casing is formed of three pieces, one consisting of the mouth piece 27, and the other two consisting of curved sheet metal pieces 28 and 29, the free edges of which are separated by a slot 30 corresponding to the slot 24 of the first construction, and their other edge portions secured by screws 31 to the lower side portions of the mouth piece. Just below the mouth piece the sheet metal pieces 28 and 29 may be indented for the two-fold purpose of giving elasticity or spring to the pieces 28 and 29, and to form stops adapted to be engaged by the longitudinal edges of the plate holder as it is turned from one extreme position to the other. In this instance, as is clear from Fig. 9, the under side of the mouth piece is curved or rounded, and the top of the plate holder bears against it.

As already stated, the instrument may have more than three reed plates, as for example, five reed plates, a five plate instrument being shown in Figs. 7 and 8, this instrument being constructed and operated precisely like the three plate instrument first described. In Figs. 7 and 8 the casing here designated 35 is formed like the casing in Figs. 1 to 5, and is provided with a projecting mouth piece 36. The five reed plates are designated 37, 38, 39, 40 and 41, these reed plates being carried by a suitable plate holder 42 having suitable chambers, cells or passageways 43 with which the reeds communicate, and adapted to be shifted as in the first instance, to render any two adjacent plates effective. The casing 35 in this instance is provided with five openings or sets of openings for the inflow or exhaust of air, these being designated respectively in Fig. 8, 44, 45, 46, 47 and 48. The middle opening 46 which is adapted to be opposite from the passageways of the mouth piece may be in the form of a slot, like the middle opening of the first described constructions.

With the plate holder in the position shown in Fig. 8, the reed plates 38 and 39 become effective, and the openings 45 and 46 are utilized one for air drawn through the

instrument, and the other for air blown through the instrument. As the plate holder is turned from one extreme position to the other, plates 37 and 38, 38 and 39, 39 and 5 40, and 40 and 41 become effective in pairs.

As the holder is turned through this range, openings 44 and 45, 45 and 46, 46 and 47, and 47 and 48 become effective in pairs for the inflow and outflow of air.

10 It is to be noted, and it is a feature of the instrument, whether of the three or five plate type, that when the holder is turned so that the upper edge of any reed plate is moved from one side of the mouth piece 15 openings to the other, the plate is converted from a blow plate to a draw plate, or vice versa. Likewise it is to be noted that when the upper ends of the cells or chambers between any pair of plates are in registration 20 with the openings of the mouth piece, the lower ends of these cells are closed, and reversely, when the lower ends of the cells between any pair of plates are in communication with an opening or set of openings of 25 the casing, for intake or exhaust of air, the upper ends of the cells are closed.

Another feature to be noted is that the middle opening or slot 24 of the three plate instrument is in one position of the holder 30 an opening for the inflow of air, and in the other position of the holder an opening for the exhaust of air, and that the same is true with respect to the middle openings 45, 46 and 47 of the five plate instrument. That 35 is to say, the openings 45 in one position of the holder are for the intake of air, and in another position of the holder are for the exhaust of air, and the same with the openings 46 and 47.

40 It is not essential to the invention that the plate holder be formed of a plurality of separate chambered spacers adapted with the reed plates to be clamped together into a unit as described in connection with Figs. 45 1 to 5, for it may be desirable to form the body of the plate holder of one piece as indicated, for example, in Figs. 8 and 9. Furthermore, it is not essential that the openings to which the mouth of the player is applied be formed in an outwardly projecting mouth piece as here shown. The instrument 50 may be modified in still other particulars without departing from the spirit and scope of my invention as defined in the appended claims.

Having described my invention, I claim:

1. A musical instrument of the harmonica type comprising a casing having a longitudinally extending perforated portion 60 through which air may be drawn or blown, and a carrier within the casing having three or more reed plates arranged side by side and extending longitudinally of the casing and spacer members between the reed plates 65 forming rows of cells between successive

plates, said cells being open at one edge of the carrier, and said carrier being movable in the casing to bring the open ends of the cells of any row into registry with said perforated portion of the casing. 70

2. A musical instrument of the harmonica type comprising a part to which the mouth of the player may be applied, said part being provided with a row of openings, and a second part movable relative to the first 75 and said second part having a plurality of rows of cells formed by a series of parallel reed plates separated by spacer members forming partitions between the cells of each row, said spacer members being so arranged 80 that each cell in a row is adapted to register with one of said openings, said parts being mounted for relative movement of one with respect to the other whereby the rows of cells may be successively brought into 85 communication with said openings.

3. A musical instrument of the harmonica type comprising a part having openings through which air may be drawn or blown by the player, and a holder movable relative to said part, said holder being provided with three or more metal reed plates arranged side by side and means forming cells between the successive plates, said cells having open ends which may be placed successively in communication with said openings by moving the holder, said holder being so mounted that it may be shifted to move an inner reed plate from one side of said openings to the other to convert it from a blow plate to a 90 draw plate. 95

4. A musical instrument of the harmonica type provided with a part having a longitudinally extending perforated portion 100 through which air may be drawn or blown by the player, and a carrier movable relative to said part, said carrier being provided with three or more reed plates and with means forming open ended cells between successive plates, which may be placed successively in communication with said perforated portion by moving the carrier, and means cooperating with any group of cells in registration with said perforated portion 105 to seal the ends thereof opposite the perforated portion. 110

5. A musical instrument of the harmonica type provided with a part having a longitudinally extending perforated portion 120 through which air may be drawn or blown by the player, a carrier movable relative to said part, said carrier being provided with three or more metal reed plates and with means forming open ended cells between successive plates which may be placed successively in communication with the perforated portion by moving the carrier, and means cooperating with the carrier to seal the cells which are in registration with said 125 perforated portion at the ends thereof 130

- posite the perforated portion and to open one or more adjacent cells to the atmosphere.
6. In a musical instrument of the harmonica type, a casing having a longitudinally extending perforated portion through which air may be drawn or blown and a cellular member mounted within the casing, said member having a plurality of rows of open ended cells arranged side by side and 10 reed plates forming side walls of said cells, said member being movable in the casing to bring any row of cells into registry with the perforated portion of the casing, said casing having additional circumferentially 15 spaced openings and imperforate portions between said spaced openings adapted to close the ends of cells in registry with said perforated portion of the casing at the ends thereof opposite said perforated portion.
- 20 7. A musical instrument of the harmonica type comprising a carrier provided with a

series of spaced reed plates and spacing members between the plates forming rows of open ended cells between successive plates which are open at the opposite edges of 25 the carrier, and a casing enclosing the carrier and yieldingly engaging opposite edges of the carrier so as to permit relative movement between the carrier and casing, said casing having a longitudinally extending 30 perforated portion adapted to register with the cells of any row and imperforate sealing portions so disposed with respect to said perforated portion that they form a seal for cells registered with said perforated portion at the ends thereof opposite the perforated portion, said casing having openings on opposite sides of said sealing portions.

In testimony whereof, I hereunto affix my signature.

GEORGE B. DUSINBERRE.
